UNITED STATES PATENT OFFICE.

FREDERICK A. JACOBS, OF KILLINGLY, CONNECTICUT.

LUG STRAP.

Application filed May 9, 1923. Serial No. 637,854.

To all whom it may concern:

Be it known that I, FREDERICK A. JACOBS, a citizen of the United States, residing at Killingly, in the county of Windham and State of Connecticut, have invented certain new and useful Improvements in Lug Straps, of which the following is a specification, reference being had therein to the accompanying drawings.

This invention relates to a lug strap, and the object of the invention is the construction of a simple and efficient lug strap that includes certain specific means for increasing the life of the strap by making the device more durable and of such construction as will resist the rapid wear of the strap, caused by the picker-stick.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a perspective view of the device constructed in accordance with the present invention, while

Figure 2 is a horizontal, sectional view of the same.

Figure 3 is a perspective view of the plug.

Referring to the drawings by numerals, 1 designates the substantially U-shaped lug strap made preferably of a plurality of layers of material, such as canvas, or the like.

Within the strap 1 I place a substantially U-shaped leather lining 2, which has its inner face beveled, at 3, to its outer ends, so as to more efficiently direct the picker-stick 4 (dotted lines) against the plug 5.

The plug 5 is preferably made of a plurality of layers of material, such as canvas, and it is concaved or curved, at 6, substantially parallel with the curvature of the closed end of the lug strap 1; in other words, the concaved face 6 of the plug 5 extends vertically so as to receive the picker-stick 4. The advantage of this structure of the plug resides in the fact that the wearing of the plug by the picker-stick will start with the picker-stick and will tend to wear down through the middle of the plug, whereas, with a plug having a convex picker-stick engaging portion the tendency is to drive the picker-stick to one side or the other and

wear out the sides of the U-shaped lug strap. Therefore, the concave plug will give, I believe, more service than any other plug, of a different structure and will tend to make the picker-stick run truer and straighter than other plugs known to the art.

Another advantage resides in the leather lining 2 which strengthens the lug strap and will glaze over after the picker-stick has run over it for a little while, so that the picker-stick will always be guided into the concave bend of the plug and will be kept away from the sides of the lug strap. It also will keep the picker-stick from wearing into the sides of the lug strap, if this wear upon the plug develops to one side or the other, and in this way will preserve the life and usefulness of the lug strap.

A rivet 7 is employed, extending horizontally through the lug strap, leather lining and plug to positively fasten the parts together and strengthening the same as it acts as a reinforcing element through the device. I also partly secure the parts of the device together by using adhesive material, or the like, in addition to the rivet 7.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. As a new article of manufacture, a device of the class described comprising a substantially U-shaped fabric lug strap, a substantially U-shaped leather lining within said lug strap, said lining provided on its inner face with beveled ends, a fabric plug within said lining provided with a concaved picker-stick engaging face in parallelism to the contour of the closed end of the lug strap, and a rivet extending transversely through the lug strap, leather lining and plug in spaced relation to the concaved face of the plug, substantially as shown and described.

2. As a new article of manufacture, a device of the character described comprising a U-shaped lug strap formed of longitudinally extending vertically disposed layers of fabric, a lining for said lug strap formed of

22
tough material and having bevelled ends terminating in spaced relation to the ends of the arms of the lug strap, a plug within said lining having a concaved picker stick engaging face, said plug being formed of vertically disposed layers of fabric having their ends terminating at the concaved face of the

plug, and a fastener passing transversely through the lug strap, lining and plug in spaced relation to the concaved face of the ¹⁰ plug.

In testimony whereof I hereunto affix my signature.

FREDERICK A. JACOBS.
